WELL PUMP

Howard J. Pankratz, Bartlesville, Okla., assignor
to Phillips Petroleum Company, a corporation
of Delaware

Application March 27, 1941, Serial No. 385,566

4 Claims. (Cl. 103—244)

This invention relates to deep well lifting apparatus and more particularly to surface controlled pumps that employ gas or air for lifting oil or other fluids from a well.

In reservoirs in which relatively large amounts of gas or at least where gas occurs in sufficient quantities to assist materially in lifting oil to the surface, it is often a serious problem to control this gas so that it can be used properly and efficiently for this purpose. As oil with its dissolved gases in the oil bearing formation flows toward and enters the well bore, pressure reduction occurs and free gas will be evolved from the oil-gas solution and dissipated at the surface of the oil in the well as lost energy unless it is properly controlled for use in the casing. When wells cease to flow naturally, it is common practice to run a string of tubing with a packer installed near the reservoir so that the energy of the gas may be used directly in lifting the oil to the surface. This method will often prolong the life of a flowing well, but, there may come a time when the ratio of gas to oil is too great and a large amount of the gas energy will be dissipated through the tubing string without doing useful work in lifting oil and the oil will be obstructed in its flow to the well bore by the creation of a gaseous condition in the sand or in the formation immediately surrounding the well. The opposite condition may exist in which the oil is predominant and there is not sufficient gas to lift all the oil that comes to the well bore and under this condition the well will cease to flow. Under either of these conditions remedial measures must be applied.

In the former case, it is common practice to segregate the gas and oil horizons either by the installation of a packer by which procedure the gas may be produced in the annular space between the tubing and the casing above the packer, and the oil produced through the tubing; or through a process of cementation in which gas is partially or entirely sealed off from the well bore and confined to the reservoir.

In the latter case, that is, in a well having a low gas-oil ratio, it is necessary to use some artificial means for lifting the oil, the most common of which is the gas lift. This method of lifting oil involves adding sufficient extraneous gas energy to cause the well to flow.

An important object of this invention is to provide a surface controlled pumping apparatus that can be adapted to a well when it ceases to flow naturally and in doing so will make use of gas energy originating in the well and which

would otherwise be wasted, or may make use of gas energy supplied from a source outside of the well, for lifting purposes.

Another object of the invention is to provide pumping apparatus of the character indicated which can be controlled from the surface and that requires only one string of tubing to operate it and conduct the well fluid to the surface. This feature also permits the apparatus to be lowered or raised to any desired point without the necessity of removing or disturbing other well equipment.

Other objects and advantages of this invention reside in its simplicity of design, low cost of construction, and ease of installation.

These and other objects not at this time more particularly enumerated will be apparent from the following detailed description and are attained by the construction shown in the accompanying drawings forming a part of this specification.

In the drawings, wherein for the purpose of illustration is shown a preferred embodiment of this invention, like numerals are employed to designate like parts throughout the same,

Figure 1 is an elevation view, partly in vertical section, showing a well equipped with pumping apparatus constructed in accordance with this invention and adapted for using extraneous gas to lift the well fluid;

Figure 2 is a similar view with the apparatus adapted for using gas evolved from the formation to lift the well fluid;

Figure 3 is a vertical sectional view through the pump proper showing the location of the packer with respect to the pump mechanism when an outside source of gas is employed;

Figure 4 is a transverse sectional view through the pumping apparatus taken on the line 4—4 of Figure 3;

Figure 5 is a similar view taken on the line 5—5 of Figure 3.

Referring now more particularly to the drawings, the numeral 12 indicates the well casing within which is the tubing string 24 attached at the surface to a power drive head 40 adapted to rotate or oscillate the tubing string. Figure 3 shows the lower end of tubing string 24 with the pump structure positioned thereon. This structure consists of a valve body 22, a valve 23 positioned therein, and a fluid accumulation chamber 13 having a perforated pipe or bull plug 10 with a standing valve 11 attached thereto. A downpipe 15 in chamber 13 completes this part of the assembly.

Valve 23 is held in valve body 22 by a ball bearing 20 and outer ring nut 18 which is threaded to the valve body 22 at its upper end. Inner ring nut 16 in turn is threaded to the tubing string 24. At the lower end bearing 21 and outer ring nut 19 serve to connect valve 23 with body 22. Inner ring nut 17 of this assembly is threaded to downpipe 15 and connects it thereto for a purpose hereinafter described.

In the upper portion of valve 23 is an axial bore 37, in alignment with tubing 24, at the lower end of which are the radial passages 36, Figures 3 and 4. Valve 23 also has an axial bore 30 in its lower part which communicates with one or more radial passages 31, Figures 3 and 5. A recessed portion 35 in valve body 22 communicates with the passages 36. Radial ports or passages 32 connect with passages 31 which in turn communicate with the axial bore 30 in valve 23. In addition to these, vertical passages 34 in valve body 22 extend from the bottom thereof to the recessed portion 35, as shown in Figures 3, 4, and 5.

Valve 23 is free to rotate or oscillate, when a turning power is applied to tubing 24 from the surface drive head 40, being rotatably mounted in relation to valve body 22 by means of bearings 20 and 21 as described above. Rotation or oscillation of valve 23 will cause passages 31 to move in to or out of communication with passages 32. Thus when valve 23 is turned so that passages 31 and 32 are in alignment, as shown in Figures 3 and 5, the annular space 33 directly communicates through axial bore 30, the interior 29 of downpipe 15, with annular space 28 in chamber member 13, and in turn by means of vertical passages 34 with recessed portion 35, passages 36, and axial bore 37 with the interior 38 of tubing string 24.

A fluid accumulation chamber is formed by the attachment of chamber member 13 to the exterior of valve body 22. Threaded to its lower end, as in conventional practice, is a perforated pipe or bull plug 10 and standing valve 11 having a ball 27 therein. Downpipe 15 is threaded by means of inner ring nut 17, to the lower end of valve 23 so that the interior 29 is in alignment with axial bore 30 of valve 23. Due to the type of construction shown in Figure 3, downpipe 15 remains stationary in relation to valve 23 which is free to rotate as above described.

Packer member 14 of standard and conventional design is set in the well so as to close the annular space between casing 12 and the pump structure as shown in Figures 1 and 2. Packer 14 is positioned either above or below the passages 32 depending upon whether the source of gas used is induced from the surface, Figures 1 and 3, or is evolved from the formation as in Figure 2. This packer 14 also serves to hold chamber member 13 with valve body 22, Figure 3, stationary in respect to well casing 12 when torque is applied to tubing string 24 from drive head 40. It should be noted that due to the construction above described, valve 23 remains free to rotate regardless of the position of packer 14.

In operation the pump assembly carrying packer 14 is suspended in the well on the tubing string 24 so that the perforated bull plug 10 extends below the fluid level. Well fluid thus enters area 26, Figure 3, raising ball 27 of standing valve 11 and flows into annular space 28 of chamber member 13. Fluid pressure may be sufficient to raise the fluid into passage 29 of down-

pipe 15 and when passages 31 and 32 are aligned, through into the annular space 33 of well casing 12. Such a condition does not hinder operations and will not often be encountered where the pump is properly positioned in the well.

When gas is evolved from a formation with sufficient volume and pressure to be utilized for lifting purposes, packer 14 is positioned above passages 32 as shown in Figure 2. Then the gas collects under packer 14 filling annular space 43 and enters passages 32. As valve 23 is turned by power transmitted from tubing string 24 and drive head 40 radial passages 31 come into alignment with passages 32 allowing the gas under pressure to flow through axial bore 30, the interior 29 of downpipe 15 into the bottom of fluid accumulation chamber 13. This gas under pressure seats ball 27 in standing valve 11 preventing further in-flow of well fluid through standing valve 11, and which also prevents pressure being exerted on the well formation.

The incoming gas under pressure from downpipe 15 is admitted to the interior 28 of chamber member 13 at the bottom thereof, see Figure 3, just above ball 27 of standing valve 11. This not only tends to secure an efficient seating of ball 27 but also causes a churning and frothing to take place within chamber member 13. A continued influx of gas then causes the froth and gassified liquid therein to rise through vertical passages 34, in valve body 22, to recessed portion 35 which communicates with radial passages 36 in valve 23, see Figures 3 and 4. Axial bore 37 in valve 23 being in communication with passages 36 and also with interior 38 of tubing string 24 completes the outlet passages for the well fluid from the interior 28 of chamber 13 to the tubing string 24 which in turn carries the well fluid to the surface in the conventional manner through the interior of drive head 40 to outlet pipe 42.

When the turning of valve 23 carries passages 31 out of alignment with passages 32 the entrance of gas under pressure from annular space 43 is cut off. Excess gas within chamber 13 exhausts from annular space 28 serving to lift the frothed well fluid into tubing string 24 through the passages above described. When the pressure within chamber member 13 has decreased below that exerted by the fluid in the well bore, ball 27 will open allowing annular space 28 to again be filled ready for another influx of gas and the cycle of operations just described including gas admission, froth formation, and ejection is repeated.

It is to be understood that the passages 31 and 32 are sized and so spaced that for any given speed of valve operation they will pass in and out of alignment allowing sufficient time for chamber member 13 to be emptied of well fluid, exhaust excess gas, and refill before gas under pressure is again admitted to the interior 28 of chamber 13.

If this invention is to be used in a well where there is not sufficient gas evolved from a formation to operate this device, an outside source of gas or air is used. Packer 14 is then placed, as shown in Figures 1 and 3, below passages 32 in valve body 22. Gas or air under pressure is admitted from the surface through connection 41 to the annular space 39 between well casing 12 and tubing string 24. It will be seen from Figure 1 that this annular space 39 and annular space 33 are continuous. This gas or air enters passages 32 and is admitted to the fluid accumu-

lation area 28 in chamber 13 when radial passages 31 and 32 are properly aligned. The alignment of passages and functioning of valve 23, gas admission, froth formation, ejection, and operating cycle are the same as above described when formation gas is used.

It is difficult to determine with what speed of rotation the valve should operate for the maximum efficiency and lowest possible gas-oil ratio without actual trials or tests in the well to be produced since conditions in no two wells are identical. Some installations operate most efficiently at a rate of approximately $\frac{1}{30}$ R. P. M., while others operate satisfactorily at speeds of approximately 3 R. P. M. It is to be understood, however, that speed of valve rotation or oscillation may be varied within wide limits at any given well and for different wells and yet remain within the range of efficient operation and that this invention is not limited to the range stated which was for illustrative purposes only.

The air or gas necessary for lifting the oil or other fluid to the surface need not be at any definite pressure. However, there will be a pressure for each given well below which the fluid will not be lifted to the surface. At pressures higher than this minimum, the oil will be lifted to the surface, and the efficiency of the operation for any given well will be dependent upon the distance the oil must be lifted, the size of the pump, the size of rotatable tubing, the air or gas pressure and other factors.

One factor to be noted in the operation of this fluid lifting pump is the frothing of the oil in the accumulation chamber 28. When the air or gas enters this accumulation chamber 13 at its bottom through downpipe 15 there is immediately formed a froth of oil and gas, and this froth is lifted from the accumulation chamber and passes out through passages 34, recessed area 35, axial bore 37 and thence into well tubing 24, as described previously, by the introduction of additional air or gas into the bottom of said accumulation chamber. The air or gas continues to enter said chamber under its driving pressure until the chamber is essentially freed of froth, the entrance of said driving air or gas being controlled by the pressure thereon and by the speed of rotation of the valve 23. Since the oil or other fluid is frothed, and froth is specifically lighter per unit of volume, the froth is therefore more easily lifted to the surface than would be a slug of relatively more dense liquid oil.

Since a froth of very low apparent specific gravity is much easier to lift than liquid oil of much higher specific gravity, the operation of this pump in any given well is relatively easy to start. This ease of starting may be contrasted with the relative difficulty of starting of conventional gas lift pumps which lift liquid oil in slugs rather than froth. This point will be understood and appreciated by those skilled in the art.

In order to absorb increased or decreased length of the rotatable tubing 24 due to thermal expansion or contraction, a slip joint of conventional design, not shown, should be installed in the tubing string near the pumping mechanism. By location of the slip joint near the pump, the latter or rather the valve 23 is not burdened in supporting excessive dead weight. If the said valve supports such a weight as that of a string of tubing, the rotating valve is soon worn and becomes out of line and in a relatively short time pump failure results.

It is to be understood that the form of the

invention, herewith shown and described, is a preferred example of the same and that various modifications may be made therein without materially departing from the spirit of this invention or the scope of the subjoined claims.

Having thus described my invention, I claim:

1. In a deep well lifting means, the combination of: a well casing; a barrel member stationary within the well casing comprising a fluid accumulation chamber and a rotatable valve associated therewith; said valve having an upper axial passage and a lower axial passage therein; a packer, and a gas accumulation chamber formed thereby between the well casing and the barrel member; a tubing string rotatably connected to the barrel member and rigidly attached to said valve, said tubing string communicating with the upper axial passage in the valve; a passage within the barrel member placing the fluid accumulation chamber in communication with the upper axial passage in the valve; a passage within the barrel member communicating with the exterior thereof to admit gas from the gas accumulation chamber to the fluid accumulation chamber upon alignment of the lower axial passage in said valve therewith; and means for controlling the flow of well fluid into the fluid accumulation chamber.

2. In a well pump, the combination of: a well casing; a barrel member stationary within the well casing containing a fluid accumulation chamber and a rotatable valve associated therewith; said fluid accumulation chamber having a check-valved opening in the lower end thereof for controlling the flow of well fluid into said chamber; the rotatable valve having an axial passage at its upper and lower ends, the upper axial passage having a radial passage connecting thereto and the lower axial passage having a radial passage connecting thereto; a tubing string attached to the said valve and rotatably connected to the barrel member at its upper end, said tubing string communicating with the upper axial passage in the valve; a passage within the barrel member placing the fluid accumulation chamber in communication with the upper axial passage in the valve; a gas inlet port within the barrel member communicating with the exterior thereof and with the fluid accumulation chamber upon alignment of the said lower axial passage in the valve therewith; and a packer member positioned between the well casing and the barrel member below the said gas inlet port.

3. In a deep well lifting means, the combination of: a well casing; a barrel member stationary within the well casing and having a fluid accumulation chamber therein and a rotatable valve associated therewith; the fluid accumulation chamber having a check-valved opening in the lower end thereof for controlling the flow of well fluid into said chamber; a tubing string suspended in the well casing rotatably attached to the barrel member and rigidly connected to said valve; said valve having an upper axial passage therein communicating with the tubing string and a lower axial passage communicating with the fluid accumulation chamber; a passage within the barrel member connecting the fluid accumulation chamber and the upper axial passage in the valve; a gas inlet passage within the barrel member communicating with the exterior thereof and with the lower axial passage in said valve at regular intervals during rotation of said valve; and a packer member

positioned between the well casing and the barrel member above the gas inlet passage.

4. In a well pump, the combination of: a well casing; a barrel member stationary within the well casing containing a fluid accumulation chamber therein and a valve body enclosing a rotatable element; the fluid accumulation chamber having a check valve in the lower end thereof to control the flow of well fluid into said chamber; a tubing string within the well casing rotatably connected to the barrel member and directly connected to the rotatable element in the valve body; said rotatable element having a passage in the upper part thereof communicating with the tubing string and a passage in the lower

part thereof communicating with the fluid accumulation chamber; a packer, and a gas accumulation chamber formed thereby between the well casing and the barrel member; a passage 5 within the valve body communicating with the passage in the upper part of the rotatable element and the fluid accumulation chamber; and a second passage within the valve body communicating with the exterior thereof to admit gas from the gas accumulation chamber to the fluid accumulation chamber upon alignment of the passage in the lower part of the rotatable element therewith.
